UNITED STATES PATENT OFFICE.

HERMANN F. CUNTZ, OF HARTFORD, CONNECTICUT, ASSIGNOR TO AMERICAN RADIUM COMPANY, OF NEW YORK, N. Y., A CORPORATION OF NEW YORK.

INDICATOR AND DIAL FOR WATCHES AND LIKE ARTICLES.

1,413,971.

Specification of Letters Patent. Patented Apr. 25, 1922.

Application filed July 2, 1921. Serial No. 482,095.

To all whom it may concern:

Be it known that I, HERMANN F. CUNTZ, a citizen of the United States, resident of the city of Hartford, county of Hartford, 5 State of Connecticut, and whose post-office address is 7 East 42nd Street, borough of Manhattan, city, county, and State of New York, have invented certain new and useful Improvements in Indicators and Dials 10 for Watches and like Articles, of which the following is a specification, reference being had to the accompanying drawings, illustrative of particular embodiments of my invention.

15 This invention relates to indicators such as the hands of clocks, watches, gauges, meters, and other devices, and also the dials for such devices and instruments, and particularly the graduations on such dials, and 20 for like or similar devices, as may appear from the following specification. Particularly in such indicators and dials the invention relates to providing them in a form or construction permitting advantageous 25 equipment with luminous material, so that the indicators or hands, or the graduations may be readily visible and readable at night, and at the same time affording accurate and easy reading of the graduations 30 or readily discerning of the indicator or indicators and their position with respect to graduations by outside light such as by daylight or when visible by ordinary illumination.

35 The application of luminous material involving compounds of radio-active and radio-responsive material, has heretofore been practised by embodying such permanently luminous compounds in a recess in 40 the hands of instruments and particularly in watch and clock hands so that a sufficient bulk of the material is held spread over a sufficient area to provide an amount of luminosity to an extent and for a sufficient distance suitable for the particular instruments or case involved; or in some cases the permanently self-luminous compound is spread over the surface of a hand or on a dial with suitable protective covering to 45 keep it in place. A reasonable area is required with a considerable width with respect to the length in a line, intended to be luminous in the dark, sufficient to provide visible luminosity at a distance of a foot or several 50 feet or yards—depending upon the particu-

lar use to which the permanently illuminated article is adapted. In view of the relatively larger width of line required for this darktime luminous effect, the indicator, hand, or pointer, or the graduation so 60 equipped, is of a greater width than permits accurate reading in the daytime or under conditions of ordinary outside illumination. It, therefore, becomes a problem 65 to provide such devices with permanently luminous material in a manner whereby accurate reading of the time or accurate reading of instruments, as to the registration of pointers with graduations can be assured or in any event can become a matter of greater 70 accuracy than has heretofore been the case by day and night.

In the case of pointers for indicators and hands for watches, a broad surface covered with radio-luminous material, backed up by 75 a relatively dark background involves all inaccuracy incident to a broad line compared with a very fine hair line or narrow marker which should be used in ordinary or full illumination for accurate determination of calibration registration. I, therefore, provide a pointer or hand with surface of a relatively sufficient width to carry an ample area of radio-luminous material for the desired degree of visibility in the 80 darkness, but I provide centrally or in the axis of such a pointer or hand, a narrow contrasting line of non-luminous material and of contrasting color with the luminous material in the daytime or when subject to 85 outside illumination. Such central line of non-luminous material provides for accurate reading in the daytime and the provision of such a line whether on the pointer, calibration, marking or numerals, supplements the art heretofore known by giving to the use of radio-luminous compound on instruments and other devices an assurance 90 of accuracy for ordinary reading which has not heretofore been the case.

In the case of a numeral or graduation, I provide accurate line or lines in the middle, or within the field of a much larger radio-luminous area, thereby supplying a well-defined distinctly readable or discernable 95 daytime marking.

The provision of such distinct non-luminous accurate mark, whether in an indicator or in a graduation, or otherwise, involves 100 modification of structures heretofore used 110

which may be provided in numerous ways but require structural changes in such parts not heretofore known and of which particular embodiments I have herewith illustrated 5 and will now describe in more detail with reference to the accompanying drawings, in which—

Figure 1 is a plan view of a pointer or hand with the daytime reading line in 10 arrow-head at the tip and centrally throughout the main body of the pointer.

Figure 2 is a plan view of a modified pointer with the daytime reading line at 15 the outer half away from the hub, terminating at the tip.

Figure 3 is a plan view of a modified pointer with the daytime reading mark full 20 length in medial position but terminating short of the tip for structural reasons hereinafter set forth.

Figure 4 is a plan view of a pointer with the daylight reading mark modified by extending the full length and terminating at the tip.

Figure 5 is a cross-section of a pointer 25 such as taken on the line 5—5 of Fig. 1.

Figure 6 is a cross-section of a pointer 30 showing a modified form of attachment for the medial daytime reading line.

Figure 7 is a cross-section of pointer with 35 a modified form of arrangement and connection between the base and the daytime reading line.

Figure 8 is a plan view of a pointer or hand 40 with modified outline and constructed to hold radio-luminous material on a portion of its length with the other non-luminous portion structurally co-operating for advantages in manufacture, durability, strength or otherwise.

Figure 9 is a side elevation of the pointer or hand shown in Fig. 8.

Figure 10 is a plan view of a fragmentary 45 portion of a dial showing a figure with daytime reading, medial mark within the field of the self-luminous figure area.

Figure 11 is a cross-section on the line 50 11—11 of Fig. 10 on a much enlarged scale.

The pointer or hand A, as for example in 55 Figs. 1 and 5, comprises a strip of very thin material and which is usually metal and preferably steel, which is formed with the usual hub a and terminates at the opposite end with its sides converging to a point a'.

As shown in these figures the middle of the 60 strip is crimped to form a ridge B, and the converging edges near the tip are turned up to form lateral converging ridges C. These ridges B and C, and particularly the

former, give a horizontal stiffness so that the strip of which the hand or pointer is made may be of thinner material than usual, with the ridge B forming a strengthening, medial flange or web. However, the height 65 of this central rib is such as to provide be-

tween it and the border or sides of the strip a recess which provides for the imbedding of a layer of radio-luminous material on either side of the central rib and extending to the edge or as near the edge of the strip as desired.

The central rib permits the imbedding of the radio-luminous material D in a manner that affords sufficient contact of the material and a vehicle or coating which holds the 75 radio-luminous material to the pointer, but also permits uniform and ready application on either side of the middle ridge, whereby the ridge is left clear and clean of luminous material and being of a contrasting color, 80 such as blued or otherwise treated steel, it constitutes a uniform dark medial line as viewed in the day time compared with the lateral areas of light-colored radio-luminous compounds. Radio-luminous compound area 85

can extend directly to the point within the converging ridges C—C whereby a pointed luminous area affords the desired visibility in the dark, while the ridges C—C protect the tip and keep the radio-luminous material 90 more permanently in position for a long period of years resisting the jarring or vibration or other effects incident to the usual usage of the pointer or hand. By providing the area in arrow-head shape, shown in Fig. 95 1, without the central parting for a short distance from the tip, the most important portion, namely, the end of the radio-luminous hand, is also better protected to resist dislodging of the radio-luminous material 100 due to any variation in temperature or in contracting of the material. Throughout the remaining length of the hand, the lateral radio-luminous material areas may be divided into sections so as to better resist 105 loosening due to contraction of the radio-luminous material and the vehicle used to secure it to the surface and to the lateral walls of the ridge.

In the form shown in Fig. 2 the medial line E comprising the crimp as shown in Fig. 5 is run to the tip a' so that a fine line which may approach the dimensions of a hair line will provide accurate reading out to the very tip during the daytime or with outside 110 illumination; and terminating the ridge E part way between the tip and the hub a makes it possible to efficiently and uniformly apply the radio-luminous material on the outer portion of the hand or pointer, for the 115 desired length of self-luminous area, and to omit it from the portion near the hub in order to save the expense of radio-active material.

In the form shown in Figure 3 the ridge 120 F provides stiffening from the hub throughout the entire length to near the tip so that the thinnest practicable material may be used for the base of the hand because such ridge provides stiffening throughout the 125 130

length; while the termination of the ridge a little short of the tip a' affords means for a small tip area of luminous compound to be lodged from side to side of the tip with 5 the end of the crimp providing the shoulder or wall to aid in holding the material which thereby forms a complete tip of radio-luminous material.

In the form shown in Figure 4, the ridge 10 G being provided from the hub a to the very extremity of the tip a' , may be readily made of the crimp B shown in Fig. 5, with respect to convenience of manufacture of the hand proper. It provides the lateral area for the 15 full length, and with the ridge G forming the shoulder for each side area, it affords the additional security for the radio-luminous compound placed on the hand, and in the manufacture after depositing the material for the self-luminosity, the artisan can 20 readily manipulate a tool across the ridge in order to clear the surface of the ridge G leaving it of the contrasting color, and in so doing it assures the uniform thickness of 25 material for luminizing in the dark the entire length of the hand.

The construction shown in Figure 6 involves the base J of the hand or pointer with a central slot into which a bent strip K is 30 forced with oppositely extending lips or flanges, which has at its outer edge the narrow surface H which may be bent or formed as rounded or flattened to provide the necessary breadth or width of the line which is 35 to form the daylight reading mark of the hand. In this form the walls of the ridge member K may be so formed as to be re-entrant to give an added value in the holding of the laterally disposed radio-luminous material.

In Figure 7 the modification in the cross-section involves the base L on one side of which a small wire M is laid and secured thereby forming a ridge to provide the 45 dial day reading line and to laterally provide for holding the radio-luminous material.

In Figures 8 and 9 a form of hand or pointer is structurally modified to the extent that the material at the hub n is compressed to form a channel for part of the 50 length adjacent to the hub with the top side N and with the lateral flanges N'. Approaching the outer end of the hand, the 55 strip is depressed, or conversely the ridge O is crimped or pressed up to the level of the surface N, forming a medial ridge preferably in the center or axis, out to the tip n' , or to such extent as may be desired for any 60 particular case with reference to the arrangements shown in the tip structures in the first four figures, or otherwise. Thus, the half of this modified form of hand nearer the outer end has on its outer side recesses 65 such as Q of a sufficient area to accommodate

an amount of radio-luminous material sufficient to assure ample visibility in the dark. The ridge O extends the stiffness of the portion N to N' to the very tip or as far as may be desired, and while providing recesses on 70 either side of the medial ridge to accommodate the radio-luminous material in a manner that does not increase the thickness of the hand beyond the thickness of the portion near the hub.

It will thus be seen that the constructions described provide a ridge or ridges intermediate the side edges of a hand or pointer, which aid to secure, and which can serve to assure uniform thickness of the radio-luminous material applied to the surface of the base. Furthermore, the ridge of rigid material forms the upper limit of the hand structure with the base at the bottom, so that both top and bottom are protected during the operation of the hands or pointers against interfering objects which might otherwise dislodge the radio-luminous material in the absence of the protecting ridge. The structure also serves to accommodate 85 most advantageously the application of radio-luminous material in different ways, as for example the principal ingredient, namely, the radio-responsive material may be very quickly applied to hands of my construction, because the ridge in its various arrangements serves to control the thickness and assure the efficiency of the application of material either in base or other form 90 with entire uniformity throughout the length 100 of the hand which it is desired to cover; thereafter the radio-active material of far lesser relative quantity may be readily dusted onto the surface or sprinkled on to the radio-responsive or sub-compound, as it is 105 sometimes called. And in any finishing operations the manipulation of the tools will be subject to the control of the ridge in conjunction with the lateral borders of the hands, whereby uniformity of finish with 110 economy in the operation is a result of great advantage from a manufacturing or studio work standpoint.

In the embodiment of the medial or daylight reading line in figures, a ridge such 115 as B, H or M may be laid on the surface of a dial or any other base where a figure or luminized device is arranged, and the recess or crevice at each side of the ridge, tapering down to the surface of the dial or other base, can with easy manipulation be filled, with the assurance of uniformity as to the maximum thickness of the radio-luminous compound, and at the same time leaving the central line 120 of contrasting color which therefore can be 125 read easily in the daytime and which has the effect of a neat, fine figure which can be made in conformity with the usual dimensions of daylight-visible figures on watch dials instead of a broad expanse of block letter. 130

When a depressed number or figure of radio-luminous material is desired the dial or base as in Figures 10 and 11 is cut out to form as there shown, for example, a figure "3" with 5 the recess T as shown in the section. In the middle of this recess a ridge or small rigid wall or flange V is embedded, the outer edge of which constitutes the fine and even hair line figure serving for daylight reading. On 10 either side of this central ridge V the radio-luminous material is applied in the cavity T constituting the area U with a sufficient expanse of surface and a sufficient bulk of material in the cavity to provide the most ad- 15 vantageous application of radio-luminous compounds. In either means of applying the night-reading material to numbers or any other figures on dials or the like the central ridge not alone provides the means of 20 producing a figure with narrow lines for daylight visibility but serves to give uniformity in limiting the depth, or the surface, of the adjacent self-luminous material; and in any way it may be applied, the best 25 or other means of application is facilitated, as well as the method of embedding or applying the sub-compound, involving the radio-responsive material, and thereafter sprinkling or dusting thereon a relatively 30 small amount of very fine radio-active material onto the surface.

It will also be realized that a narrow line provided in the structure of hands or dials as heretofore described, as well as many 35 modifications thereof, supplies a daytime visibility of a fine hair line which may be so narrow that it will in no way interfere with the luminosity in darkness of the adjacent radio-luminous areas. The light 40 emission from radio-luminous areas is such that with a total area, and with a width of luminous line in proportion to its length, sufficient for the desired legibility in the dark for a watch or clock or any other par- 45 ticular use, means that such light emission will have substantially the value of the entire area of the hand or figure, and for night observation the narrow uncoated central ridge will not appear, i. e., it will practically 50 be bridged by the light emission from the adjacent luminous areas.

Conversely, hands or figures constructed and formed as heretofore described may be of white or light tints matching the adja- 55 cent enamel color of a dial underlying the hand, in which cases watches or clocks with their reading parts so constructed will have in daytime a substantially invisible breadth of hand, but a narrow clearly visible line, 60 even a hair line, will constitute the central, indicating or reading marking for the hand and for the dial marking or figure with just as great accuracy for daylight use as any ordinary watch, clock or other indicating de- 65 vice,—and with no apparent increased

breadth in the markings or hands during daytime reading.

The revolutionary development involved in the introduction of readable-in-the-dark watches, clocks, compasses and other indicating instruments and devices, is well-known to have involved at first the serious objection of making very broad hands and either large dots for graduations or broad figures in order to provide a sufficient area so 75 that the permanent self-luminosity or radio-luminous materials would serve the night reading object. The clumsiness of such structures impeded for years the more general adoption of the day and night reading- 80 parts of timepieces and other instruments, and the necessity for providing means so that the same night visible instruments would be equally readable by day, led to the provision of a border, or more properly two borders, 85 one on either side of the self-luminous area. Such borders on broad hands were an initial objection criticized as "clumsiness", which the general usefulness of the self-luminous markings has but partially overcome. Initial 90 attempts in the case of some instruments led to the use of a contrasting background, so that the white hand was bordered by a dark background but this only made day reading 95 relatively visible but still involved the broad and inaccurate mark which is white for day reading and has the same objections for many classes of timepieces as well as other devices. Added to the solution of the problem of producing reading parts of timepieces 100 or other devices which can be accurately read in the daytime, it will be seen that the structures heretofore described have many added advantages, such as assuring uniformity in the amount or depth of the coating of radio-luminous material, and stiffening the pointers and permitting the use of the thinnest obtainable sheet material for 105 the base of hands or pointers in order to reduce the total thickness of the hands as well 110 as to provide uniformity throughout the length of area of the luminous surfaces. Other advantages will be appreciated in the practice of this invention, facilitates for manufacture, as well as economies and speed 115 of production with uniformity of product, add to the value of durability and other characteristics of the finished product.

While various modifications may be made in the structure and arrangement as well as 120 the material and use of the articles, of which specific embodiments have been heretofore described, I do not confine my invention to the specific forms shown in the accompanying drawing and herein specified in detail 125 but what I claim and desire to secure by Letters Patent is:

1. A hand for watches and other indicators comprising a longitudinal extending area of radio-luminous material and a cen- 130

tral non-luminous longitudinal line of contrasting color when viewed with outside illumination.

2. An indicator or pointer for timepieces or like articles comprising a long, narrow strip coated from side to side with permanently self-luminous material and a single medial line of contrasting surface visible in the daytime.
- 10 3. A pointer or hand for timepieces and the like comprising a surface coating of radio-luminous material and an area providing visibility in the dark from the outer end and substantially extending toward the hub, of a single line formed of non-luminous material having a contrasting surface extending medially through said luminous area.
- 20 4. An article of the character described comprising a thin base strip of metal of a single medial ridge extending the major length of the axis.
- 25 5. An article of the character described comprising a thin, flat base, a single central rib formed on said base centrally from a point near the tip and extending intermediate the sides of the strip towards the center of the hub.

6. An article of the character described comprising a hub, a flat base, a coating of radio-luminous material secured to said base and a central ridge secured to said base extending in a line radially from the axis of the hub to a point in close proximity to the outer end.

7. An article of the character described having a base of thin flat material and a crimp formed in the middle on a line radial to the center of the hub.

8. An article of the character described comprising a base of thin sheet material, a medial ridge of similar material projecting from the top side, radio-luminous material imbedded on either side of said ridge between the walls of the ridge and a lateral border of the base.

In testimony whereof, I have signed my name to this specification, in the presence of two subscribing witnesses, this 1st day of 50 July, 1921.

HERMANN F. CUNTZ.
